[57] CLAIM

The ornamental design for a direct station selection console, substantially as shown and described.

DESCRIPTION

FIG. 1 is a top front isometric view of a direct station selection console, showing our new design;

FIG. 2 is a top plan view thereof;

FIG. 3 is a front elevation thereof;

FIG. 4 is a right side elevation thereof;

FIG. 5 is a left side elevation thereof;

FIG. 6 is a rear elevation thereof; and

FIG. 7 is a bottom plan view thereof.
